DRY SHAVING APPARATUS

Lorenzo O'Russo, Princeville, Ill.

Application February 15, 1946, Serial No. 647,972

15. Claims. (Cl. 30—43)

1 This invention relates to shaving implements of the type commonly known as dry shavers, and it includes certain features in the nature of hair clipping mechanism adapted for use in connection with the shaving operation.

In most dry shaving devices now in use an oscillating or rotating cutter moves under a perforated guard through which the hairs protrude so that the edges of the perforations cooperate with the moving edges of the cutter for shearing the hair. However, in order that the hairs may be readily entered in the perforations, these openings in the guard or screen element are several times larger than the diameter of a human hair; consequently, a single hair entering one of these perforations may stand much nearer one side of the opening than the other. Whether or not it is efficiently attacked by the moving cutter will depend upon the direction from which the cutter approaches a hair thus positioned in the opening. A rotating cutter approaches from only one direction and an oscillating cutter is limited to two directions of approach, neither of which may be the most efficient for cooperating with the edge of a perforation nearest which the hair happens to stand.

One object of the present invention is to provide a new and improved dry shaving apparatus having means adapted to approach and engage the hair more efficiently than has been possible with previous devices.

Another object of the invention is to provide a dry shaving apparatus in which the cutting element is arranged for a four-way cutting movement enabling it to cooperate with an apertured fixed cutter so as to accomplish faster and closer shaving than has been possible heretofore.

It is also an object of the invention to provide a dry shaving apparatus having a relatively simple operating mechanism which is economical to manufacture and adapted to operate satisfactorily for a long period without replacement or repair.

More specifically, it is an object of the invention to provide a dry shaving apparatus having a fixed perforated guard or cutter element and a movable cutter element which includes a blade, or blades, arranged for oscillation in contact with the fixed cutter and also having other blades or cutters which reciprocate with respect to the fixed perforated element so that hairs inserted in any of the perforations will be engaged from any of four directions with the practical certainty of being promptly and closely severed.

Other objects and advantages of the invention

will appear from the following description taken in connection with the drawings, in which:

Fig. 1 is a longitudinal sectional view of a shaving apparatus embodying this invention, including a suitable electric driving motor for the cutter;

Fig. 2 is a fragmentary detail section taken at right angles to the plane of Fig. 1 as indicated at line 2—2 on Fig. 1, and on a larger scale, with certain parts broken away;

Fig. 3 is an end elevation of the device with a portion of the stationary guard or cutter broken away to reveal the movable cutter which cooperates with it;

Fig. 4 is a detail sectional view taken as indicated at line 4—4 on Fig. 2, showing the movable cutter at the middle of its range of oscillation;

Fig. 5 is a view similar to Fig. 4, showing the cutter at one limit of its range of movement;

Fig. 6 is a view similar to Fig. 4, showing the cutter at the other limit of its range;

Fig. 7 is a sectional view similar to Fig. 2 but showing a modified construction, which includes cutting slots at the end of the guard member to operate in the manner of a clipper;

Fig. 8 is a transverse section taken as indicated at line 8—8 on Fig. 7;

Fig. 9 is an external perspective view of the cutter head shown in Figs. 7 and 8;

Fig. 10 is a transverse detail section showing a modified form of cutter and guard, made with square openings in both of said elements;

Fig. 11 is a sectional view on a larger scale taken as indicated at line 11—11 on Fig. 10;

Fig. 12 is a perspective view of the movable cutter element employed in Figs. 10 and 11;

Fig. 13 is a fragmentary plan view of a portion of the perforated area of the cutter and its guard showing said parts in registered relation and showing the square perforations on a much enlarged scale;

Fig. 14 is a section taken as indicated at line 14—14 on Fig. 13;

Fig. 15 is a sectional view similar to Fig. 2, showing another modified form of the invention;

Fig. 16 is a transverse section taken as indicated at line 16—16 on Fig. 15;

Fig. 17 is a fragmentary end view of the structure shown in Fig. 15 with a portion of the guard broken away to show the cutter;

Fig. 18 is a view similar to Fig. 15, showing a further modification;

Fig. 19 is a detail section taken as indicated at line 19—19 on Fig. 18;

Fig. 20 is a fragmentary detail section showing an additional form of the invention, the section being taken at a plane through the axis of oscillation of the blade;

Fig. 21 is a transverse section taken as indicated at line 21—21 on Fig. 20;

Fig. 22 is a fragmentary perspective view showing portions of the blade and skin guard in assembled relation;

Fig. 23 is a fragmentary end view of the device shown in Fig. 20, but with parts of the housing broken away, and with some parts shown in section;

Fig. 24 is a fragmentary view showing a modified arrangement of the cutting blade in the type of mechanism shown in Figs. 20 to 23.

For purposes of illustration the dry shaving implement shown in Fig. 1 is of substantially conventional outline and includes a driving motor which may be similar to those now in use. The frame or body 10, which encloses the motor, is of convenient form and dimensions to be held in the hand, and the motor includes a rotary armature 12 having its shaft 14 journaled in bearings 16 and 18. A suitable electric cable is indicated at 20 and is provided with a detachable plug 22 for connection with any convenient outlet providing a source of current.

The shaving head includes a removable housing or guard 24 shown as retained in position in the end of the body 10 by spring-pressed ball detents 26 so that it can be pulled out for cleaning or repair. Figs. 1 and 3 show the guard 24 formed with ribs or corrugations 25 in its side walls below the arcuate portion to facilitate grasping the guard in removing it. The end of the frame or body 10 is formed with a recess or chamber 28 in which a shaft 30 is carried on floating bearings 32 which are supported by springs 33 urging said bearings and the shaft outwardly toward the curved perforated portion 34 of the guard member 24.

In this form of the device the cutter is shown as a cylinder 36 provided with a bushing sleeve 38 which is slidably fitted on the shaft 30, and the cylinder is formed with a socket 40 for operative engagement with a crank pin 42 carried by a disc or flange 44 on the end of the motor shaft 14. Preferably, the end of the crank pin 42 is of spherical form, fitting snugly but with running clearance in the socket 40 so that rotation of the motor shaft 14 causes the cylinder 36 to oscillate about the axis of its shaft 30 and also to reciprocate simultaneously on said shaft, the socket 40 being disposed radially in the cylinder 36.

The cylinder 36 is subdivided into a plurality of circumferentially extending cutters 46 spaced apart by grooves 48, each cutter having two sharp circular cutting edges which cooperate in shearing relation with the edges of the perforations 50 in the curved portion 34 of the guard as the cylinder reciprocates on its shaft 30. The cylinder is also formed with a longitudinal slot 52 in which there is secured a straight cutting blade 54, preferably in diametrically opposite relation to the socket 40 so that this blade sweeps over the inner surface 45 of the curved guard portion 34 and cooperates in shearing relation with the edges of the perforations therein as the cylinder 36 is oscillated on its axis by rotation of the crank pin 42.

With this arrangement it will be seen that

a hair entered in one of the perforations 50 will be subjected to the cutting action of a circular cutting edge of one of the blades 46 moving in one direction, and to the cutting action of another circular cutting edge moving in the opposite direction as the cylinder 36 is reciprocated on the shaft 30; and since the cylinder is simultaneously oscillated about its axis, such a hair may be approached and severed by one edge of the blade 54 moving toward it or by the opposite edge approaching it from the opposite direction in the reverse portion of the oscillation of the cylinder 36. The severance may be accomplished by the first cutting edge which engages the hair, but if not, or if the hair is not in position to be severed close to the skin by the first edge which encounters it, a second cut by another cutting edge approaching from a different direction is quite certain to accomplish this. With the shaft 14 running at any reasonably high speed, a hair protruding through one of the holes 50 in the guard 34 will be subjected to four successive cutting strokes from four different directions, all within a fraction of a second after it is entered through the guard, so that close severance of the hair becomes a practical certainty.

Preferably, the middle area of the curved guard portion 34 is provided with the holes indicated at 50, but at each side of this area elongated slots or openings 56 are formed within the arc which measures the range of oscillation of the blade 54, so that the longer hairs of the beard may be first and more easily engaged in those slots with subsequent insertion through the holes 50 in final and close shaving.

Figures 7, 8, and 9 show a modified structure in which the guard element 60 is formed with holes 61 over most of its working face, but has slots 62 of angular formation at the arcuate marginal edges of its working surface. These slots facilitate clipping or trimming the longer hairs of a mustache or sideburns in conjunction with a regular shaving operation. To render the slots 62 effective, the straight blade 64 which is oscillated about the axis of shaft 66 occupies the full width of the space inside the guard 60 and is fitted for close engagement with the inner arcuate surface and with the flat surfaces 68 of the end walls of the guard so as to perform a shearing function in cooperation with the L-shaped inner edges of the slots 62. The arcuate cutters 70 are supported in a carrier 72 which is attached to a cross head 74 slidably mounted on the shaft 66 so that the rotary motion of the crank pin 76 driven by the motor shaft 78 reciprocates the blades 70 past the perforations 61 of the guard 60 and simultaneously oscillates the blade 64 with which the carrier 72 is slidably engaged. The shaft 66 is mounted in floating bearings 80 carried on springs 82 for yieldingly pressing the blades 64 and 70 into contact with the cooperating guard 60. The cutters 70 may be made integral with the carrier member 72 if desired. In this structure the flat end walls of the guard element 60 may be grasped for removing the guard, and as shown in Fig. 9, these end walls are slotted at 61 to clear the shaft 66 of the cutter.

In the form of the device shown in Figs. 10 to 14, both the guard member 90 and the oscillating cutter 92 are formed of sheet metal with perforations which provide the cutting edges. The guard member 90 is secured in the end of the body 94 by spring-pressed ball detents 96 and its outer

end is of cylindrical form, curved about the axis of a shaft 98 which may be journaled in suitable bearings in body 94, similar to the bearings shown in the structure of Fig. 7. The cutter 92 is curved to form something more than half a cylinder as indicated in Fig. 10, with a straight narrow tie member 100 connecting the ends of the curved portion along a chord of its circular outline and supporting a hub 102 which is slidable on the shaft 98 and a radial socket 104 which engages the spherical end of the crank pin 106 driven by the motor shaft 108. As shown in Fig. 11, the hub 102 and the socket 104 may be integral, with the socket portion 104 extending through a suitable opening in the bridge or tie member 100 and secured by collet 110 as indicated in Fig. 12. Necessarily Figs. 10, 11, and 12 are only diagrammatic in their illustration of the perforations in the cutter and guard; these features are more accurately shown in Figs. 13 and 14. The perforations in the guard 90 and in the cutter 92 may be of square form, as shown in Fig. 13, and may register with each other at one position of the parts, as shown in this view and in Fig. 14. It may be assumed that the width of each square opening is from six to eight times the diameter of a human hair, while the bars between the openings are much narrower than the openings themselves; thus, even though the blade 92 is oscillated at considerable speed, there will be ample opportunity for the hairs of the beard to be entered through the openings of the guard and cutter so as to be sheared off by the movement of the cutter as it oscillates in contact with the inner surface of the guard 90. As the crank pin 106 rotates, the hub 102 is caused to slide and also to oscillate on the shaft 98 carrying with it the cutter member 92. The shaft 98 may be carried on floating bearings 112 with springs 114 to maintain contact between the parts 90 and 92.

A further modification of the invention is shown in Figs. 15, 16, and 17 in which the structure closely resembles that of Figs. 1 to 6, with one exception. The cylindrical cutter member 116 is formed with two sets of grooves 118 disposed respectively at opposite sides of the straight blade 120, and in staggered relation to each other, thus exposing staggered sections of the straight blade 120 at its opposite cutting edges. As the member 116 oscillates, the grooves will uncover first one set of holes in the guard member 122 and then a different set, so that substantially all the holes in the part 122 are eventually brought into play to furnish cooperating cutting edges. Fig. 16 shows ribs or corrugations formed at 125 in the side walls of the guard to facilitate its removal.

In the arrangement shown in Figs. 18 and 19, the oscillating member 130 has arcuate cutters 132 formed at intervals in the length of the member 130 and carries a single straight blade 134 in a radial slot, as seen in Fig. 19. The middle portion of the outer surface of the member 130 is cut down along a chord of its cylindrical form, forming flat surfaces 136 at each side of the blade 134, thus exposing both cutting edges of the blade 134 for their entire length. As shown in Fig. 18, this blade 134 extends throughout the full width of the perforated guard 138 and the blade is slidably engaged with the part 130 so that the latter, with its arcuate blades 132, can reciprocate. With this arrangement, the blade 134 may also be slidable radially so that centrifugal force will urge it outwardly against the curved guard member 138. The arcuate cutting edges of the upstanding blades 132 being cut down at their

middle portions do not extend to the straight blade 134 but the oscillation of the member 130 will cause the segments of these blades 132 to register with the perforated area of the guard 138, while the reciprocatory movement of the carrier 130 will give them a cutting action in cooperation with the edges of the holes in the guard. Both movements are produced by rotation of the crank pin 140 driven by the motor shaft 142 and operating in the same manner as the driving mechanisms of the structures already described.

Figures 20 to 23 illustrate a shaving apparatus which, to some extent, resembles those already described. It includes a motor shaft 150 driving a crank pin 154, but in this case the cutter blade 156 has only an oscillatory movement produced by engagement of the crank pin 154 in a longitudinally extending slot 158 in the driving arm 160 which extends from the blade carrier 162. The carrier is provided with a shaft 164 to which it may be fixed, said shaft being journaled in floating bearings 166 mounted on springs 168 and guided for movement in the end portion of the body 170. The blade carrier includes a pair of arms 172 extending from the body portion 162 of the carrier and these arms support the blade 156 in radial grooves.

In this structure, the cooperating cutting element is in the form of an outer guard or housing 174, having a single slot 176 which provides a pair of oppositely facing cutting edges to cooperate with the edges of the blade 156 as it sweeps past the slot 176. The blade carries with it a skin guard element 178 which is of arcuate cross section with alternating slots 180 and bars 182 which are secured to the blade 156, the bars being flush with the cutting edges of the blade so that only the alternate portions of said edges which register with the slots 180 are actually exposed for cutting action. The slots 180 permit the hairs of the beard to protrude through the single slot 176 in the path of the cutter blade 156 as it oscillates, and the bars or ribs 182 prevent the adjacent skin of the face from being forced too deeply into the slot 176. In Fig. 21 the guard is shown with ribs or corrugations 184 in its side walls below the arcuate portion to facilitate grasping it for removal.

In Fig. 24, I have shown a modification of this type of mechanism in which the oscillating blade 157 is slightly oblique to the edges of the slot 177, so that as the blade oscillates its cutting action in cooperation with the edges of the slot proceeds progressively along these cutting edges, thus somewhat reducing the load on the driving motor and insuring a somewhat smoother operation.

While I have illustrated and described herein several forms of my invention, it is to be understood that the invention may assume numerous other forms and that it includes all modifications, variations and equivalents coming within the scope of the appended claims.

I claim:

1. In a shaving implement, an arcuate guard member perforated to act as a cutting element and providing cutting edges transverse to its axis of curvature and cutting edges disposed along lines parallel to said axis, a movable cutter to cooperate with said guard, said cutter having a plurality of cutting edges disposed in planes transverse to its longitudinal axis and a longitudinally extending peripheral slot, a blade in said slot forming cutting edges in planes substantially normal to the plane of said first mentioned cutting edges, and means to oscillate said cutter

about the axis of curvature of said guard and to reciprocate the cutter along said axis simultaneously.

2. In a shaving implement, an arcuate guard member perforated to act as a cutting element and providing cutting edges transverse to its axis of curvature and cutting edges disposed along lines parallel to said axis, a movable cutter to cooperate with said guard, said cutter having a plurality of cutting edges disposed in planes transverse of its longitudinal axis and a longitudinally extending peripheral slot, a blade in said slot forming cutting edges in planes substantially normal to the plane of said first mentioned cutting edges, and means to oscillate said cutter about the axis of curvature of said guard and to reciprocate the cutter along said axis simultaneously, together with bearing means for said cutter and means yieldingly urging said bearing means toward the guard member to hold the cutter in shearing engagement with the edges of the perforations in said guard.

3. In a shaving implement, an arcuate guard member perforated to act as a cutting element and providing cutting edges transverse to its axis of curvature and cutting edges disposed along lines parallel to said axis, a movable cutter having an arcuate form fitting within said guard, said cutter having a plurality of cutting edges disposed in planes transverse to its longitudinal axis and a longitudinally extending peripheral slot, a blade in said slot forming cutting edges in planes substantially normal to the plane of said first mentioned cutting edges, a shaft disposed in substantially coaxial relation to said guard, said cutter being slideable on said shaft and means to oscillate said cutter about the axis of said shaft and to reciprocate said cutter on the shaft simultaneously.

4. In a shaving implement, an arcuate guard member perforated to act as a cutting element, cutter means to cooperate therewith comprising a cutter member having at least a portion of its periphery of generally cylindrical form provided with circumferentially disposed grooves forming curved cutting edges at intervals in its length and an independent longitudinally extending blade carried by said cylindrical portion having cutting edges intersecting said curved cutting edges and substantially flush therewith, and means to oscillate the cutter member about its axis and reciprocate it simultaneously along said axis, said guard member including end walls connected to its arcuate portion, and said longitudinally extending blade being slidably engaged with the cylindrical portion of the cutter member and fitting closely between said end walls, whereby the cylindrical portion of the cutter member reciprocates relatively to said blade and said blade is actuated by the oscillation of the cutter member.

5. In a shaving implement, an arcuate guard member perforated to act as a cutting element, cutter means to cooperate therewith comprising a cutter member having at least a portion of its periphery of generally cylindrical form provided with circumferentially disposed grooves forming curved cutting edges at intervals in its length and an independent longitudinally extending blade carried by said cylindrical portion having cutting edges intersecting said curved cutting edges and substantially flush therewith, and means to oscillate the cutter member about its axis and reciprocate it simultaneously along said axis, said guard member including end walls con-

nected to its arcuate portion, and said longitudinally extending blade being slidably engaged with the cylindrical portion of the cutter member and fitting closely between said end walls, whereby the cylindrical portion of the cutter member reciprocates relatively to said blade and said blade is actuated by the oscillation of the cutter member, said guard having slots extending radially in its end walls at the junctions thereof with the arcuate portion and extending longitudinally in said arcuate portion adjacent said junctions, and said blade having cutting edges at its ends to cooperate with said slots as said blade is oscillated.

15 6. In a shaving implement as defined in claim 1, the perforations of said arcuate member each having a width equal to several times the diameter of a human hair, the movable cutter comprising an arcuate member also formed with perforations each having a width several times the diameter of a human hair, and said cutter having a range of oscillation and a range of reciprocation each exceeding the said width of its perforations.

20 7. In a shaving implement as defined in claim 1, the perforations of said arcuate member being square and each having a width equal to several times the diameter of a human hair, the movable cutter comprising an arcuate member also formed with square perforations each having a width several times the diameter of a human hair, and said cutter having a range of oscillation and a range of reciprocation each exceeding the said width of its perforations.

25 8. In a shaving implement as defined in claim 3, said means including a rotary shaft journaled at an axis perpendicular to the axis of the first mentioned shaft, said cutter having a radially disposed socket, and a crank on said rotary shaft engaged in said socket, whereby the rotary shaft simultaneously oscillates and reciprocates the cutter.

30 9. In a shaving implement as defined in claim 3, said means including a rotary shaft journaled at an axis perpendicular to the axis of the first mentioned shaft, said cutter having a radially disposed socket, and a crank on said rotary shaft engaged in said socket, whereby the rotary shaft simultaneously oscillates and reciprocates the cutter, together with a frame supporting said guard member, bearings for the cutter shaft slideable in said frame toward and from the guard, and spring means yieldingly urging said bearings toward the guard to maintain shearing engagement of the cutter with said guard member, said crank having a spherical end portion fitting closely in said socket throughout the range of movement of the cutter.

35 10. In a shaving implement, an arcuate guard member perforated to act as a cutting element, cutter means to cooperate therewith comprising a cutter member having at least a portion of its periphery of generally cylindrical form provided with circumferentially disposed grooves forming curved cutting edges at intervals in its length and an independent longitudinally extending blade carried by said cylindrical portion having cutting edges intersecting said curved cutting edges and substantially flush therewith, and means to oscillate the cutter member about its axis and reciprocate it simultaneously along said axis, the cylindrical portion of the cutter member having a longitudinally extending generally radial slot, and said blade being slideable radially 40 in the slot and being held in cutting engagement.

with the perforated guard member by centrifugal force generated by the oscillatory movement of the cutter member.

11. In a shaving implement, a guard member having an arcuate portion perforated to act as a cutting member, cutter means to cooperate therewith including a blade having a longitudinal cutting edge for engaging the arcuate portion and extending substantially parallel to the axis of said guard member, and means to oscillate said blade about said axis, said guard including end walls joined to its arcuate portion, the end walls being perpendicular to the axis of the arcuate portion, said guard having slots extending outwardly in its end walls to the junctions thereof with the arcuate portion and thence extending longitudinally in said arcuate portion adjacent said junctions, and said blade having generally radial cutting edges at its ends intersecting said longitudinal edge to cooperate with said slots as the blade is oscillated.

12. In a shaving implement, an arcuate guard member perforated to act as a cutting element and providing cutting edges transverse to its axis of curvature and cutting edges disposed along lines parallel to said axis, cutter means to cooperate therewith comprising a member of generally cylindrical form with circumferentially disposed grooves alternating with ribs which provide curved cutting edges transverse to the axis of the member at intervals in its length, a peripheral slot in said member, a longitudinally extending blade in said slot having cutting edges intersecting said curved cutting edges and substantially flush therewith, the grooves in said cylindrical member at one side of the longitudinally extending blade being disposed in registration with the ribs in said member at the opposite side of said blade whereby oscillation of the cutter in one direction causes it to cooperate with a different area of the arcuate guard member than that with which it cooperates in its movement in the opposite direction.

13. In a shaving implement, a guard member having a thin generally cylindrical portion perforated to act as a cutting element, a movable cutter means including an outer generally cylindrical peripheral portion for engaging the guard, the cylindrical portion of the cutter means being provided with a plurality of spaced generally circumferential grooves and intermediate arcuate guard-engaging ridges and with a generally longitudinal groove transversely intersecting the circumferential grooves, a blade carried by the cylindrical portion of the cutter means positioned in the longitudinal groove providing generally longitudinal cutting edges substantially flush with the ridges, means to move the cutter means with respect to the guard for producing oscillations of the cutter means about its cylindrical axis, said guard being perforated with a plurality of apertures individually having generally circumferential and generally longitudinal cutting edges, the arcuate ridges having sharp cutting edges, and the means to move the cutter means reciprocating the cutter means along its axis simultaneously with the oscillations thereof.

14. In a shaving implement, a guard member having a thin generally cylindrical portion per-

forated to act as a cutting element, a movable cutter means including an outer generally cylindrical peripheral portion for engaging the guard, the cylindrical portion of the cutter means being provided with a plurality of spaced generally circumferential grooves and intermediate arcuate guard-engaging ridges and with a generally longitudinal groove transversely intersecting the circumferential grooves, a blade carried by the cylindrical portion of the cutter means positioned in the longitudinal groove providing generally longitudinal cutting edges substantially flush with the ridges, means to move the cutter means with respect to the guard for producing oscillations of the cutter means about its cylindrical axis, the guard being perforated with a longitudinal slot having opposite longitudinal cutting edges for cooperation with the longitudinal blade, and the arcuate ridges forming skin supporting means to limit the extent of entrance of skin into the slot during shaving.

15. In a shaving implement, a guard member having a thin generally cylindrical portion perforated to act as a cutting element, a movable cutter means including an outer generally cylindrical peripheral portion for engaging the guard, the cylindrical portion of the cutter means being provided with a plurality of spaced generally circumferential grooves and intermediate arcuate guard-engaging ridges and with a generally longitudinal groove transversely intersecting the circumferential grooves, a blade carried by the cylindrical portion of the cutter means positioned in the longitudinal groove providing generally longitudinal cutting edges substantially flush with the ridges, means to move the cutter means with respect to the guard for producing oscillations of the cutter means about its cylindrical axis, the generally longitudinal groove extending in such a direction that the blade positioned in the groove is slightly oblique to the slot, whereby the cooperative cutting action proceeds progressively along the edges of the slot as the blade is oscillated.
